UNITED STATES PATENT OFFICE.

OTTO A. MARTINI, OF BROOKLYN, NEW YORK, ASSIGNOR TO UNDERWOOD TYPEWRITER COMPANY, OF NEW YORK, N. Y., A CORPORATION OF DELAWARE.

TYPE-WRITING MACHINE.

1,227,061.

Specification of Letters Patent. Patented May 22, 1917.

Application filed December 28, 1916. Serial No. 139,303.

To all whom it may concern:

Be it known that I, OTTO A. MARTINI, a subject of the King of Denmark, residing in Brooklyn borough, in the county of Kings, city and State of New York, have invented certain new and useful Improvements in Type-Writing Machines, of which the following is a specification.

This invention relates to an improvement 10 in typewriters, and more especially to a change in construction of the tabulating finger-pieces.

Where tabulating mechanism is used to space the carriage, it is often desirable, in 15 addition to spacing to the various decimal digit columns, to also space to the punctuation points, such as the comma between hundreds and thousands and the decimal point between dollars and cents. On the 20 other hand, some types of work do not need this particular control, and, in order to increase the capacity of the tabulating mechanism, it is desired that digits instead of punctuation marks shall be used in the cor- 25 responding places. In order to avoid confusion, the tabulating key heads or finger-pieces are made reversible, so as to expose to view either one of a series of characters or signs, indicating the particular digit col- 30 ums, such as hundreds, thousands, tens of thousands, etc., to which the particular keys correspond.

Ordinarily decimal tabulating keys control, successively, selections in each zone or 35 major column. In certain kinds of work it is desired, however, sometimes to skip some of the zones or major columns, and bring the carriage to some zone or column farther down the line. A mechanism, then, has 40 been invented, described in the patent to Barnard, 1,073,068, for selectively positioning the carriage, either in succession or otherwise, at the beginning of any one of a series of major columns or zones within the 45 capacity of the machine. In the present exemplification of the invention, there are shown four zones or major columns. Some of the same decimal tabulating keys, with the aid of a special key, are used to control 50 the tabulating and auxiliary mechanism to select zonal positions of the carriage. It is desired, then, that these keys have a designation thereon showing which particular columns may control, such as the first, sec- 55 ond, third and fourth columns. These signs are always visible as they might be of use

when either of the other two sets of characters on the tabulating keys are in use. This third character or designation must be arranged so as not to interfere with the 60 other signs on the keys. Further, inasmuch as the change from depressing one decimal tabulating sign to another is made by rotating a shutter, the sign, for indicating the column, which is placed on the shutter, 65 should be in an upright position for the showing of either of the other sets of characters. To do this, the shutter carries an indicator with the column sign thereon. The indicator is mounted on a pinion meshing 70 with a fixed annular gear. The ratio between the fixed pinion and the annular gear is such that in the two positions of the key head, the column sign will be correctly shown and not inverted, as would be the 75 case if it was just swung around with the shutter.

Other features and advantages will hereinafter appear.

Referring to the drawings,

Figure 1 is an assembled view of the front parts of the tabulating keys, showing the series of characters having the punctuation-space signs as covered, and exposing to view the other set, thereby giving the great- 85 est digital capacity of the tabulating mechanism.

Fig. 2 is a view of one of the tabulating key heads or finger-pieces, showing it in just the opposite position to that of Fig. 1, 90 whereby it indicates thousands instead of tens of thousands.

Fig. 3 is a spread perspective view showing the various parts of the improvement detached one from the other to bring out 95 the details thereof.

Fig. 4 is an enlarged view of one of the tabulator key finger-pieces showing the same in vertical section from front to rear.

Fig. 5 is a diagrammatic vertical section 100 of the type-writer in general, showing the mechanism for obtaining either decimal typewriting or column selecting.

Referring to the specific parts of the invention, 1 indicates tabulating keys which control a combined decimal tabulating and column-selecting mechanism, indicated in general at 2, for determining various positions of the carriage 3. A detailed description of this mechanism 2 need not be given 105 here, as it is not a part of this invention and is disclosed in the patent to Barnard, 110

1,073,068. It is sufficient to say that this mechanism enables the tabulating keys 1 to either control decimal positions successively in the several major columns or zones, or 5 select any one of the major columns or zones, not necessarily in successive order.

There are ten of these tabulating keys shown corresponding to ten letter-space positions of the carriage 3. Some of these 10 spaces may be used for punctuation in certain classes of work. If that is the case, the capacity of the column or zone, and likewise the tabulating mechanism for selecting 15 digital columns, is less than it would be if all of the letter-spaces of a zone were used solely to furnish places for digits.

The keys 1, as shown in Fig. 1, are each provided with two sets of designations or characters. One set is as follows: . 1 10 100 20 T 10T 100T M 10M and 100M. The other set of characters, which is covered up in Fig. 1 is: . 1 10 100, T 10T 100T, and M. Four of these keys, which are arranged to control the column selection, are also provided with the characters 1, 2, 3 and 4 25 designating the first, second, third and fourth columns which they select.

Each tabulating key includes a stem 4 having a base 5 secured thereon. This base 30 is recessed to form a nest for a disk 6 on which are printed the characters for indicating the two decimal or letter-spaces which the key selects. For example, the key indicated at 7, in Fig. 1, has printed on the 35 front half of the disk 6, the designation T indicating thousands, and on the upper half a comma (shown dotted), indicating in the other series the punctuation space between 40 hundreds and thousands. The particular 45 form of the disk 6 will be seen by reference to Fig. 3. This disk has two lugs 8 engaging in corresponding sockets 9 in the base 5 so as to prevent its rotating.

Fixed to the base 5, there is provided a 45 collar 10 formed with an inwardly-projecting flange 11 having formed thereon an internal gear 12. Meshing with this gear 12 is a pinion 13 provided with an indicator 14 having inscribed thereon, in the case of four 50 of the keys, the designations, 1, 2, 3, 4, for the four zones or major columns controlled by the tabulating mechanism. The indicator 14 projects into a corresponding opening 15 in a shutter 16. This shutter is 55 mounted to rotate relatively to the collar 10 and the base 5. The shutter is also provided with a sight-opening 17, through which one or the other characters on the disk 6 is 60 visible, according to the position of the shutter with respect to the tabulating key. That is to say, if the shutter is in the position indicated in Figs. 1 and 3, the lower character on each numeral key will be visible, whereas, if it is reversed by rotation thereof to the

position indicated in Fig. 2, the upper 65 character will be visible.

It will be noted, in passing, that the indicator 14, on such of the keys as are provided therewith, forms part of the shutter in concealing the characters over which they 70 lie. The shutter 16 is secured to a cap 18 slipped over the shutter and over parts on the key base 5. This cap may be provided with an inwardly-curved annular flange 19 to engage a transparent disk 20 placed above 75 the shutter 16 and indicator 14. The cap is also provided with tabs 21 bent over to engage the under side of the base 5 to hold the parts in their disassembled position on the tabulator key to extend forward. 80

It will be seen then that the cap 18 may be rotated from the Fig. 1 position to the Fig. 2 position, whereby the shutter will bring the sight-opening 17 therein from a position disclosing the lower character on 85 the corresponding tabulator key to a position disclosing the upper character, as in Fig. 2. The character on the indicator 14 corresponding to the zone or major column will always be visible as its surface is flush 90 with the upper surface of the shutter. This character will be in an erect position in both positions of adjustment of the cap and parts carried thereby, as it rotates with the cap and shutter, and the ratio of its pinion 13 95 to the annular gear 12 is such as to compensate for the half reversion in inverting the position of the shutter. The particular ratio used in this instance is one to three, but might be any other ratio found feasible. 100

To lock the cap and shutter in the two positions of adjustment thereof, there is provided a ball lock 22 normally urged outward by a spring 23 provided in a socket in the base 5. This ball 22 passes through an 105 opening 24 in the collar 10 and into either one of two openings 25 and 26 provided on opposite sides of the shutter 16. This locking arrangement is sufficient to hold the parts against accidental relative movement, 110 but will yield when considerable force is applied to permit a change in exposing one or the other set of characters. The special form of shutter and indicator is only necessary for the four keys which have the three 115 sets of characters thereon. The other keys which have but two sets of characters may have a simple shutter, such as that disclosed in the patent to McLaughlin, 980,547.

In order to keep the pinion 13 from rubbing off the characters on the disk 6, and also to decrease the friction, the pinion 13 is supported in a raised position above the surface of the disk 6. To do this, the recess in the base 5 is made slightly deeper than 125 the thickness of the disk 6, so that the rim of the base 5 will form part of the supporting means for the pinion 13. To support

the pinion 13 adjacent the center of the base 5, there is provided a miniature turn-table or button 27 rotatably mounted at the center of the base 5. This turn-table is also of 5 slightly greater thickness than the disk 6 and its upper surface is flush with the surface of the rim surrounding the disk 6. The pinion 13, then, will have a practically rolling engagement with the rim of the base 5 and the turn-table 27, so that it will turn 10 easily and will clear the characters on the disk 6.

It will thus be seen that those tabulating keys which are used to control both decimal 15 or digit column selecting, and zone or major column selecting may have three designations thereon, two of which being alternately visible, with a third for the zone being always visible and maintained in a vertical 20 position in either of its positions of adjustment.

Variations may be resorted to within the scope of the invention, and portions of the improvements may be used without others.

Having thus described my invention, I claim:

1. The combination with a key, of a reversible cap for said key, and a perpetual indicator having a sign thereon reversing 30 with said cap while maintaining the upright position of the sign on the key in obverse or reverse positions.

2. The combination with a key stem, of an indicator on said key stem having a sign 35 thereon and turning to reverse the position of the indicator, and compensating means for automatically correcting the inversion of the sign, so as to maintain the same in an upright position in either position of adjustment on the key stem.

3. The combination with a key stem, of a character on said key stem, a shutter shift- 45 able to alternately disclose and conceal said character, a second character moving with said shutter, and means for maintaining the second character in erect position in either position of the shutter.

4. The combination with a key stem, of a disk on said key stem having two signs 50 thereon, a shutter for alternately disclosing and concealing said signs separately, and an indicator having a sign thereon moving as said shutter moves and relative thereto, to assume in each position of said shutter a position corresponding to an upright showing of the sign on the indicator.

5. The combination with a key stem, of a disk on said key stem having signs thereon, a shutter for alternately disclosing and concealing said signs, a stationary gear, a gear 60 moving with the movement of said shutter, and an indicator adjusted by said gears, so that a sign thereon will be maintained in a justified position in different positions of 65 said shutter and indicator.

6. The combination with a key stem, of a disk on said key stem having characters thereon, a shutter rotating relatively to said key stem to alternately disclose and conceal said characters, said shutter having a sight- 70 opening and a second aperture, an indicator extending in said second aperture, and having a character thereon, and a differential mechanism effective during a relative movement between said shutter and said indicator 75 with respect to said key stem to correct a reversion of said indicator, so as to maintain the sign thereon in correct position.

7. The combination with a key stem, of a disk mounted on said key stem having a plurality of characters thereon, a shutter rotatably mounted on said key stem to alternately conceal and disclose said characters, 80 said shutter having a sight-opening and a second aperture therein, an indicator extending in said second aperture, and having a character thereon, a gear connected to said key stem, and a gear meshing with said first-mentioned gear connected to said indicator, 85 said indicator swinging through an arc with the rotation of said shutter and rotating relatively to said shutter to maintain the character thereon in an upright position in different positions of said shutter and said indicator. 90

8. The combination with a key stem, of a disk on said key stem having different characters thereon to indicate different determinations of the associated key, an indicator having a sign thereon swinging from a position over one of said characters to a position over another of said characters, and differential means compensating for the swinging of 100 said indicator about a fixed point so as to cause the sign thereon to assume a vertical 105 position in both positions of the indicator.

9. The combination with a key stem, of an indicator on said key stem having a character thereon, a shutter, and gearing enabling a relative movement between said indicator and said shutter for a swinging movement of said indicator while maintaining the character on said indicator in an erect position. 110

10. The combination with a key stem, of a disk having characters thereon mounted on 115 said key stem, a member rotating above said disk, and supports for said member projecting circumferentially and centrally somewhat above the surface of said disk, to enable said member to clear said disk. 120

11. The combination with a key stem, of a base on said key stem, said base having a recess therein, a disk having characters thereon in said recess with its upper surface 125 located somewhat below the upper surface of the rim of said base, said disk having a central opening therein, a member rotatably mounted in said central opening and having its upper surface on a higher level than the 130

upper surface of said disk, and a pinion rotating around said base supported by said member and said rim, out of contact with said disk.

5 12. The combination with a key stem, of a base on said key stem, a disk on said base having characters thereon, a shutter for alternately disclosing and concealing said

characters, a floating indicator traveling with said shutter above said disk, and supporting means for maintaining said indicator out of contact with said disk. 10
